UNITED STATES PATENT OFFICE.

HERBERT J. SCHLUCKEBIER, OF FRANKENMUTH, MICHIGAN.

TIE-HANGER.

1,283,324.

Specification of Letters Patent.

Patented Oct. 29, 1918.

Application filed November 24, 1917. Serial No. 203,698.

To all whom it may concern:

Be it known that I, HERBERT J. SCHLUCKEBIER, a citizen of the United States, residing at Frankenmuth, in the county of Saginaw and State of Michigan, have invented new and useful Improvements in Tie-Hangers, of which the following is a specification.

This invention relates to a tie hanger or holder, designed particularly for use in supporting and shaping neckties of the four-in-hand type, the object of the invention being to provide a hanger by means of which a tie may be suspended from a suitable support and kept in shape.

15 A further object of the invention is to provide a tie hanger and shaper which is simple of construction, reliable and efficient in action, and by means of which the material of the tie will be smoothed out and kept 20 free from wrinkles while it is being supported between periods of use.

The invention consists of the features of construction, combination and arrangement of parts, hereinafter fully described and 25 claimed, reference being had to the accompanying drawing, in which:—

Figure 1 is a view showing my improved tie hanger and shaper with a tie applied thereto.

30 Fig. 2 is a vertical transverse section through the tie frame and tie.

Fig. 3 is a view of the hanger with the tie removed therefrom.

Fig. 4 is a view showing a detail of construction.

In carrying my invention into practice, I provide a tie hanger and shaper comprising a V-shaped frame 1 formed of spring wire, the arms 2 and 3 of which frame are 40 integrally connected at the vertex, as shown at 4, the frame as a whole being thus preferably bent into form from a single piece of spring wire.

The arms 2 and 3 are provided at their 45 free, divergent ends with backturned portions forming eyes 5. These eyes 5 slidably and pivotally engage the oppositely extending arms 6 of a handle or suspending device 7, the ends of the arms 6 being bent at right angles, as shown at 8, to form stops to limit the outward sliding movement of the eyes 5 and to hold the parts against disconnection and displacement.

The handle or suspending device 7 also 55 preferably consists of a single piece of wire, the wire being centrally bent upon itself to

form a ring-shaped or looped handle or suspending member 9, thence having its ends intertwined to form a stem or shank 10 holding the handle loop closed and connecting the same with the arms 6, which arms 6 project laterally in opposite directions therefrom.

By reason of the slidable and pivotal connection between the frame arms 2 and 3 and 65 the arms 6 of the handle, the frame arms 2 and 3 are adapted to have relative inward and outward movement to adapt the frame to conform to the width of the tie to which it is applied and also to permit said arms 2 70 and 3 to expand or move apart by their spring action to exert pressure upon the material of the tie to distend the same and thereby smooth out the material and eliminate all wrinkles, whereby the tie will be 75 at all times preserved in shape while suspended or supported by the device. The pivotal connection between the handle and suspending device also adapts the suspending device to be swung inwardly to dispose 80 the hand loop 9 between the frame arms 2 and 3, when the device is not in use, so that the hanger may be packed in close compass for storage or transportation.

In the use of the device for supporting 85 and shaping a tie, the frame 1 is inserted into the body portion of the tie 11 between the front and rear plies thereof, the arms 2 and 3 by their resiliency or spring action being yieldable to conform to the width of 90 the tie, and by their tendency to spread engaging the side edges of the tie body along the lines of fold between the front and rear plies thereof, as a result of which the fabric of the tie will be spread out to eliminate all 95 wrinkles or creases and thus give proper form or shape to the tie while it is being suspended or supported. The tie thus fitted on the frame may be hung by the handle from any suitable support, and the free end of 100 the tie may be allowed to hang loose or may be pinned to the body of the tie, as desired. By supporting the tie when not in use in this manner the tie may be compactly stored and kept in proper shape between periods of 105 use, as will be readily understood, and by folding the handle between the frame arms it will be evident that the hanger may be disposed in compact form so as to be conveniently carried in a suit case or other receptacle or otherwise packed for storage or 110 transportation.

Having thus fully described my invention,
I claim:

5 A tie hanger and shaper comprising a V-shaped frame formed of spring wire, the free ends of the arms of said frame being provided with eyes, and a suspending device formed of wire and comprising a central portion formed to provide a looped handle, intermediate portions intertwined together and forming a rigid shank projecting from said handle, and end portions pro-

viding arms projecting in longitudinal alignment with each other and bent at right angles to and in opposite directions from said shank, said arms being slidably and 15 pivotally engaged by the eyes of the frame arms and bent at their free ends so as to form terminal stops to limit the spreading movements of said frame arms.

20 In testimony whereof I affix my signature.

HERBERT J. SCHLUCKEBIER.
